UNITED STATES PATENT OFFICE.

EUGENE BERNINGHAUS, OF CINCINNATI, OHIO.

BARBER'S CHAIR.

SPECIFICATION forming part of Letters Patent No. 270,572, dated January 16, 1883.

Application filed July 18, 1882. (No model.)

To all whom it may concern:

Be it known that I, EUGENE BERNINGHAUS, of Cincinnati, in the county of Hamilton and State of Ohio, have invented a new and useful 5 Improvement in Barber-Chairs, which improvement is fully set forth in the following specification and accompanying drawings, in which—

Figure 1 is a perspective elevation of the 10 improved chair with the seat removed. Fig. 2 is a perspective view of the revolving seat frame. Fig. 3 is a vertical sectional view of the revolving seat base and the frame. Fig. 4 is a cross vertical section of the chair-frame 15 and revolving seat base; Fig. 5, an enlarged top or plan view of the spring and foot-lever, partly in section.

The object of the present invention is to provide an improved barber-chair; and it consists 20 in having a frame provided with a flat top in which is a circular aperture. Upon this top is placed a base-piece, which lies flat, and is provided with gibs on the under side to hold it to the chair-top. The ends of the base- 25 piece have standards, which are hinged to the chair-seat, and a foot-lever is also hinged to the under side of the chair-seat and projects downward within the circular aperture of the frame-top, and is provided with notches or 30 teeth, which engage with the rim of the circular top. The base-piece has centrally a downwardly-projecting limb, from which two arms project backwardly, so as to permit the notched lever to operate between said arms, a coiled 35 spring being interposed between the downwardly-projecting limb of the base-piece and the notched lever to keep the latter in position against the inner rim of the circular top.

It further consists in providing the ends of 40 the revolving seat base with forwardly-projecting extensions, to which are hinged the upper ends of the arms, attached to the foot board or rest, all of which will now be described in detail.

45 In the accompanying drawings, A represents the legs of a chair having a flat top, B, which is provided with a recess or central circular aperture, C. On this top is a cross-piece, D, having midway a forwardly-projecting piece, E, and at the ends two forward extensions, F

F, as shown. On the under side of the main cross-piece and the central forwardly-projecting piece E are gibs G, which serve to hold the piece D to the top B, but at the same time permit it to turn on the top. To the forwardly-projecting end pieces, F, are hinged the arms H, which are rigidly secured to the foot board or rest I. The foot-board has casters or rollers J, so that as the cross-piece D rotates on the top the foot-piece I will also be 60 carried around. The cross-piece D has also projecting upward from each end the vertical standards K, which are hinged to the brackets L. The chair-seat (not shown) rests on these brackets, the latter being secured thereto by 65 screws or bolts through the brackets. The seat, when thus secured, may be tilted backward and forward on these standards. The cross-piece D, with its forwardly-projecting limbs E F, and the standards K, are preferably 70 cast in one piece. On the rear side of the cross-piece D, centrally, is a depending or downwardly-projecting limb, M, having at its lower end two rearwardly-projecting horizontal prongs or arms, N. These arms carry a 75 cross-head, O, which is provided on the rear side with two lugs or spurs, P, between which the foot-lever operates. A coiled spring, Q, is interposed between the cross-head O and depending limb M, so that the force of the said 80 spring will keep the lever R against the inner rim of the top B. The foot-lever R is preferably slightly bent, and provided on its rear edge with notches S. This lever rests against the cross-head O, between the spurs P, and is 85 hinged at its upper end to the bracket T, which bracket is in turn permanently secured to the under side of the chair-seat, in common with the brackets L, heretofore described. The tendency of the coiled spring Q is to keep the 90 notches on the rear side of the lever R securely in the rim of the top B, and at the same time to prevent the cross-piece D from moving rearwardly. The cross-piece D and its accessories are therefore rotated together on the top B. 95

When it is desired to tilt the chair-seat backward or forward the foot of the operator is placed on the rest at the lower end of the lever R and pushed forwardly. This releases the teeth from the inner rim of the top B, when 100

the seat is tilted in the desired direction and the foot withdrawn from the lever, when the notches S will again hold it in position.

Having described my invention, what I claim is—

1. In barber-chairs, the top B, provided with a circular opening, C, in combination with the cross-piece D, having the forwardly-projecting arms E F, the standards K, carrying the seat, the depending limb M, having the rearwardly-projecting arms N, cross-head O, spring Q, and the notched lever R, also hinged to the seat at the upper end, substantially as and for the purpose set forth.
2. The flat top B, having a circular aperture, to which the seat is secured so that it may be revolved thereon, and the lever for tilting the chair, hinged to the seat and depending therefrom within the circular aperture, substantially as herein specified.

3. In barber-chairs, the foot-rest hinged to the revolving base, to which the seat is hinged, so that the said foot-piece may be raised or lowered or rotated with the seat, substantially as herein set forth.

4. In barber-chairs, the cross-piece D, having the depending limb M and its accessories, as shown, the notched lever R, the standards K, and brackets L T, hinged thereto, carrying the seat, the forwardly-projecting arm E, and the gibs G, in combination with the hinged foot-rest I, substantially as herein shown.

In testimony that I claim the foregoing I have hereunto set my hand, this 30th day of June, 1882, in the presence of witnesses.

EUGENE BERNINGHAUS.
